CONTROL FOR POWER PRESSES

Wallace F. Gayring, Minoa, N. Y., assignor to
 The Prosperity Company, Inc., Syracuse, N. Y.,
 a corporation of New York

Application April 25, 1944, Serial No. 532,604

1 Claim. (Cl. 38—40)

This invention relates to machines having an opening and closing movement, as garment pressing machines having one of the pressing elements, as the movable upper element or head heated as by a fluid heating medium, as steam, or electrically, etc., and has for its object a machine including a cabinet in which the heat is retained or prevented from radiating to the atmosphere within the room, which may be kept at a uniform temperature and humidity or air conditioned, and also means for insulating the heat or confining it by far for the most part within the cabinet during the closing and opening of the machine.

The invention also has for its object a safety control consisting of a single operator-operated member, as a manual, which, to effect the closing of the press, is but momentarily operated, together with a member, as a heat shield which moves with the movable pressing element or head as the press closes and which controls means for de-energizing the actuating means effecting the closing of the press, if the shield encounters an obstruction, all whereby the operator merely momentarily operates the manual and does not wait for the press to close, but the closing of the press is prevented in the event the operator attempts to do any further work in correcting the lay of the article on the lower pressing element, after operating the manual, and while the press is closing. It also has for its object a heat insulating guard or curtain extending across the face of the movable pressing element when the press is open and movable out of this position, as the press closes, this being preferably used with and operated by the shield. It may be used with or without the cabinet and the shield.

Safety controls for machines of this type have, for the most part, heretofore been two hand controls which required the operator to hold two manuals depressed until the press closed. This operation permitted a quick closing of the press head but required that the operator stay at the machine and hold down the two manuals until the press did close. The operator's time, however, is a greater desideratum than the operating time of the press, especially where the operator attends more than one machine and passes immediately from one machine, after operating its manual to close the press, to another machine.

The invention consists in the novel features and in the combinations and constructions hereinafter set forth and claimed.

In describing this invention, reference is had

to the accompanying drawings, in which like characters designate corresponding parts in all the views.

Figure 1 is an elevation of this machine, when open, with a cabinet shown in section.

Figure 2 is a side elevation showing the position of the movable shield when the press is closed.

Figure 3 is a front elevation, partly in section, of the machine shown in Figure 1, that is, when the press is open.

Figure 4 is a diagrammatic view showing the control and actuating mechanisms for the movable shield guard and the movable pressing element or head.

Figure 5 shows arrangement of three presses tended by one operator.

This machine comprises, generally, mechanism for carrying out an underlying new method of 20 operation of a machine which is enclosed in a heat insulated cabinet, this method consisting in the operator merely momentarily operating a manual, which controls power actuating means effecting the movement of a shield telescoping 25 within the hood of the cabinet downwardly over the lower pressing element or buck, and in so doing, effecting the actuation of power to a power actuating means, which effects the closing movement of the press head slowly to follow up the 30 shield therewith but slightly behind the front edge of the shield toward closed position, and automatically disabling the motor of the actuating means, if the shield comes in contact with an obstruction, as the hand of the operator attempting to smooth out the garment on a lower 35 pressing element or buck at the last moment. The invention consists broadly and more or less specifically in mechanism for carrying out this method, and if desired, heat insulating the hot head by a curtain guard normally extending 40 across the face of the hot head and movable by the closing movement of the shield out of its normal position, this guard protecting the operator from coming in contact with the hot head 45 when arranging an article on the lower pressing element and also protecting him from heat radiating from the head, when the press is open.

The pressing machine embodying the illustrated form of the invention comprises, generally, in its 50 entirety, a suitable frame, a heat insulated cabinet enclosing the frame, cooperating pressing elements, as upper and lower elements having a relative opening and closing movement, one, as the lower pressing element or buck being carried by the frame outside the cabinet, the upper press-

ing element or head having the opening and closing movement; the cabinet including a stationary hood enclosing the pressing element or head when the head is in upward or open position, a shield movable into and out of the hood and also including the movable pressing element, this shield being open at its front and rear sides but closed at its lateral sides and top and movable out of the hood to form an extension of the hood during the closing of the press, a heat insulating guard or curtain normally closing the front open side of the shield and extending across the pressing face of the head, the guard being controlled in its movement by the shield during the movement of the shield out of the hood to uncover the pressing face, power actuating means for the shield, power actuating means for the press head controlled in its operation by the movement of the shield actuating means, and means controlled by the shield when it is obstructed during the closing movement of the press to disable the power actuating means for the press head, and a single operating member for initiating the flow of power to the actuating means for the shield. Some of the elements may be omitted.

1 designates the frame of the pressing machine; 2 the lower pressing element or buck mounted on the frame above a horizontal table 3 on the top forward side of the frame. 4 designates the movable press head, this being here shown as carried by the forward arm of a lever 5 pivotally mounted between its ends at 6 on an upright 7 rising from the frame 1. The head 4, however, may be carried in any suitable manner.

8 designates a heat insulated cabinet including the hood 9 on the upper side of the cabinet, this hood being open at its front side overhanging the table 3 and closed at its rear and lateral sides and top. 10 designates a hood-shaped shield telescoping within the hood 9 and normally contained within the hood 9, when the press head 4 is open, this being open at its front and rear sides and closed at its lateral sides and top. The shield 10 encloses the head 4 and the arm of the operating lever 5, which carries the head 4. The shield 10 is here illustrated as pivoted at 11 at its lower end to the side walls of the cabinet 8 near the axis 6 of the head carrying lever 5.

12 designates a burn guard or heat insulating curtain normally closing the front side of the shield 10 and hence of the hood 9, this running over suitable guide rollers 13 near the top arcuate wall of the shield 10 and being anchored at one end at 14 to the stationary hood 9 and connected at its other end to springs 15, which springs are anchored at 16 to the side walls of the hood 9 or the main part of the cabinet 8. The front portion of this guard or curtain 12 thus extends across the pressing face of the head 4, which is heated, and when the press is open, confines the heat within the cabinet and prevents it from radiating into the face of the operator or into the room in which the machine is located. It also prevents the operator from coming in contact with the press head when the press is open. During the operation of the machine, the actuating means for the shield 10 operates to move it from its position shown in Figure 1 to that shown in dotted line (Figure 1) or full line (Figure 2). During this movement, the curtain gradually withdraws upwardly, so that the face of the press head is exposed, as it nears the surface of the buck 2 or the work thereon, and

5 during this movement, the springs 15 are additionally loaded. As seen in Figure 3, these springs are connected to the opposite ends of a transverse rod 18 at the lower end of the guard or curtain 12 and at 16 to the hood.

10 During the closing movement of the shield 10, the press head 4 follows up the shield and its movement is controlled by the actuating means for the shield 10 which in turn also controls the movement of the curtain 12. The closing movement of the head 4 is further controlled by means, which disables the actuating means for the head 4, when the shield 10 or the advance edge thereof 15 encounters an obstruction during the closing movement of the press. The advance edge of the shield is well in advance of the press head.

15 The actuating means here illustrated comprises pneumatic motors, as cylinders and pistons. 19 designates the cylinder and 20 the piston of the motor for operating the shield 10. This motor is mounted to have a floating, or bodily shifting movement under the reaction of the air in the cylinder against the cylinder head, when the piston is obstructed in its movement, and in so operating under the reaction to disable the motor for actuating the press head 4, as will be presently described.

20 As here shown, the cylinder is carried by one arm of the lever 21 pivoted at 22 between its ends to the frame 1 or any other fixed part, and connected at its other end to a spring 23 which normally holds the lever from movement under the reaction of the air in the cylinder 19. The rod 24 of the piston is shown as pivoted at its upper end at 25 to a lever arm 26 extending radially from the pivot 11 of the shield 10.

25 27 designates the cylinder and 28 the piston in the cylinder of the motor for actuating the head 4. This is an oscillating cylinder pivoted at 29 to the base of the frame. The rod 30 of the piston is here shown as connected at 31 to the joint of a toggle consisting of links 33, 34 pivoted at their outer ends respectively at 35 to the frame and at 36 to the rearward arm of the head carrying lever 5. When the piston 28 is actuated, the toggle 34 is straightened, thus actuating the head 4 toward closed position. The closing movement is against the action of returning spring 31. This form of actuating mechanism is merely illustrative and any suitable actuating or motion transmitting mechanism may be used.

30 38 designates a control valve operated by a manual, as a lever 39 located at the front of the machine or the table thereof. The valve may be 55 of any suitable form, size and construction, and it is here shown as self-locking. It includes a suitable casing normally arranged with its intake head 41 closed and its exhaust head 42 open, the valve member being held and returned to its normal position, as by a spring 43. The valve member is actuated by the lever 39 here shown as pivoted at 44 and having an arm 45 which through another lever, for a purpose to be described, actuates the stem 47 of the valve member 40. The intake end of the valve 38 is connected to a main line 48 for a motive fluid as air. Upon operation of the manual lever 39 upwardly from the position shown in Figure 4, the arm 45 through the interposed end of the lever 46 actuates the movable member 40 of the valve 38 to close its exhaust valve head 42 and open its intake valve head 41, permitting air to pass from the main line past the open head 41 through duct 49 in the valve casing to one side of a diaphragm 50 in a diaphragm chamber 51, actuating the dia-

phragm 50 to shift a sliding stem 52 against the lever 46 and hold the lever 46 and hence the valve member 40 in its operated position, this happening upon momentary operation of the lever 39.

The air also passes from the valve casing 38 through conduits 53, 54 to the lower intake end of the cylinder 19 to actuate the piston 20 on its up stroke and move the shield 10 out of the hood 9 toward the dotted line position (Figure 1) and full line position (Figure 2). At the same time, the air passes from conduit 53 to conduit 55 and a pressure reducing or throttle valve 56, conduits 58 and 60 to the lower end of the cylinder 21 to actuate the piston 28 on its power stroke, the air pressure being reduced below main line air pressure to such an extent that the actuation of the piston 28 is so slow as to actuate the head 4 slowly on its closing movement and to merely follow up the closing movement of the shield 10. The pressure reducing or throttle valve 56 may be of any well known construction. As the shield 10 is moving toward closed position, the heat insulating guard 10 is being withdrawn across the pressing face of the head 4 and clears the head when the shield 10 is a short distance over the work on the buck 2. When the shield 10 reaches its closed position, its arm 26 has moved to the dotted line position (Figure 4), where it comes in contact with a yieldingly pressed thimble 61 on the stem 62 of the movable member 63 of a combined intake and exhaust valve, here shown as of the same type as the valve 38. In so doing, it opens the intake valve head 65 and closes the exhaust valve head 66. The intake end of the casing of the valve 64 is connected by conduits 67 and 68 directly into the main feed pipe 48. When the intake of the valve 64 is opened and the exhaust 66 closed, air passes through the valve 64 and conduit 68 to the conduit 60, and thence to the cylinder 21 to actuate the piston 28 with full air pressure and close the press into final closed position. A suitable check valve 69 is located in the conduit 68.

The press is opened by operating the manual 39 downwardly (Figure 4), thus operating an exhaust valve 70 by exhausting the air from the pressure side of the diaphragm chamber 51 through conduits 71, 72 or by a timer 73, which may, for the present, be ignored, thus permitting the movable member 40 to be operated by the spring 43 to close its intake head 41 and open its exhaust 42, permitting air to exhaust back from the cylinder 19, pipes 53, 54, casing of valve 38 out through the exhaust EX. As the piston 20 returns to its starting position, as will be presently described, the arm 26 moves out of contact with the head 61 on the valve member 63 of the valve 64 and permits the intake valve head 65 to close and the exhaust to open, permitting the air to exhaust back from the main cylinder 21 through the pipes 60, 58 past the check valve 560 of the reducing valve 56, thence back through pipes 55, 53 and casing of the valve 38 out through the exhaust passage EX thereof, the spring 37 reacting to return the piston 28 to its starting position. In some instances, a timer 73 is employed to time the opening of the press. 73 designates such a timer, this being of the type known as the tank timer, that is, pressure builds up in a tank to a predetermined degree when it operates a diaphragm which opens an exhaust valve. The degree of pressure required or the time required to build up the pressure may be adjusted by means of an adjusting screw or member 74

75 from zero to maximum. 75 designates the exhaust valve of the timer. When the timer is used, the pressure builds up in the tank thereof from the pressure side of the diaphragm chamber 51 through the pipe 72, until it overcomes a diaphragm in a diaphragm chamber 76, which, through a lever 77, opens the exhaust valve 75 which discharges into the outer air directly, as indicated by the arrows 78. However, with the timer, the press may be opened at any time by operating the manual 39 downwardly to exhaust the pressure in the tank 73 through the pipe 71, and hence from the diaphragm chamber 51 through the pipe 72 by opening the valve head 79 of the exhaust valve 70 against its returning spring.

The cylinder and piston motor 21, 28 is disabled by the shield 10 or the advance edge thereof coming in contact with an obstruction, as the hand 20 of the operator. The stopping of shield 10 is illustrated by dot-dash lines (Figure 1). When the shield 10 comes in contact with such an obstruction, the shield 10 is momentarily stopped. This causes the reaction of the air on the piston 20 to move the cylinder 19 bodily downward, thus moving the lever 21 on its pivot against the action of a spring 23. Such movement causes the lever to open the normally closed valve head 80 of an exhaust valve 81 against the action of its spring 82, this valve being connected to conduits 83, 84 to the conduit 58, so that the cylinder 21 is opened to the exhaust of air, and the piston 28 free to return to starting position under the influence of the spring 37. Thus the press head 4 opens, although the shield 10 does not return, and may, when the obstruction is removed, continue on to its fully closed position. However, if this occurs, the obstructing force being removed, the cylinder 19 returns upwardly to its normal position under the pull of the spring 23, so that the exhaust valve head 80 is again closed and the cylinder 21 open to the intake of air. Hence, the press will be then closed, although the shield 10 is and has been in closed position.

The piston 20 is returned to starting position when the press opens by air pressure constantly applied to the upper side of the piston 20, through conduit 85 connected to the upper end of the cylinder 19 and to the conduit 68, which is connected in the main line. There is thus a differential pressure on opposite sides of the piston 20, but the pressure face on the lower side of the piston 20 is greater than that on the upper side, because the pressure area of the piston on the upper side is reduced an amount dependent upon the diameter of the piston rod 24. Hence, when the conduit 54 is opened to the main line of air pressure, as when the valve 38 is open, the pressure on the lower side of the piston 20 is greater than 60 and overcomes the pressure on the upper face of the piston 20. When, however, the intake valve head of the valve 38 is closed, and the exhaust valve head opened, the pressure on the upper side of the piston 20 predominates and the piston 20 returns to its starting position under air pressure taken direct from the main line through the conduit 85.

The cabinet is provided with a suitable exhausting fan 86, the outlet 87 of which may be connected to a chimney or other duct leading to the outside. This heat may be reclaimed or used for conditioning of garments.

Owing to this control and the shield, a press of this type may be safely operated with one hand and by a momentary operation, thus eliminating

the time the operator has heretofore been required to expend in waiting for the press head to close. As shown in Figure 5, three presses A, B and C are operated by one operator. After placing garment on press A, she operates control 38 and immediately leaves for press B and so on to press C, et al. On conventional presses, she is compelled to stand at machine until it closes and then move to next press. By this method, operator's time is saved and complete safety is provided. Because of the cabinet 10 and guard 12, the temperature of the room in which the machines are located may be air-conditioned and the temperature and humidity kept constant, and further no appreciable amount of heat radiates from the press head at any time into the face of the operator.

What I claim is:

In a pressing machine, a frame, a heat insulating cabinet enclosing the frame, upper and lower cooperating pressing elements, the upper element being movable toward and from the lower, the lower element being carried by the frame outside of the cabinet, and means supported by the frame for carrying the movable upper pressing element, the cabinet including a hood portion in

which the movable element is normally located, the hood portion having an opening through which the upper pressing element is movable during the opening and closing movement, an imperforate shield movable out of and into the hooded portion and movable out of the same in advance of the movable pressing element, the shield having imperforate top and side walls telescoping in the hood portion, the lower wall of the shield being open, a closure for normally closing the opening of the hood and the opening of the shield, and operating mechanism operable upon each machine operation to move the shield out of the hood into position to cover the other pressing element and work thereon in advance of the closing movement of the movable pressing element, open the closure means and operate the upper pressing element into pressing coaction with the lower pressing element, and to operate the movable pressing element, shield and closure means in the reverse order upon opening of the press, whereby there is a minimum of exchange of atmosphere between the interior and exterior of the cabinet during the press operation.

WALLACE F. GAYRING.
